HEAD PIECE FOR LOUVERS

Edward C. Hallock, Summit, N.J.

Application February 28, 1957, Serial No. 45,026

Term of patent 14 years

(Cl. D54—2)

FIG.1.

FIG.4.

FIG.2.

FIG.3.

I claim:

The ornamental design for a head piece for louvers, as shown.
